AUTOMATIC SHEAR RELEASING MECHANISM FOR FABRIC SHEARING MACHINES

Angelo Andreotto, Clifton, N. J., assignor to Botany Worsted Mills, Passaic, N. J., a corporation of New Jersey

Application November 21, 1942, Serial No. 466,519

5 Claims. (Cl. 26—17)

In the finishing of woolen fabric it is customary to sew a plurality of fabric pieces into a long continuous length preliminary to the action of a shearing device for removing the face nap of the fabric in order that the texture may be properly brought out. Thus contiguous pieces of fabric are joined at their ends by seams at either overlapped or abutted edges, the latter seam requiring, of course, an edge overlaid stitching. In either case this seam must be protected from the action of the rotary shear, and hence it has been customary to employ a hand-operated device for relatively moving the fabric and shear as the seam approaches the shear. The result is that at the ends of each fabric piece there remains a considerable unsheared section. It is the object of the present invention to greatly reduce this unsheared area at the joining ends of the fabric pieces by means very rapid and wholly automatic in its action.

The invention will be described with reference to the accompanying drawings, in which:

Figure 1 is fragmentary view, in elevation, showing the forward portion of a shearing machine, said portion having been stripped of mechanism, except that directly related to the elements forming the subject of the invention, certain elements being shown in section.

Figure 2 is a fragmentary view, in elevation, partly in section, showing the fluid pressure actuator and the solenoid-operated valve for the pressure line.

Figure 3 is a plan view of the embodiment shown in Figure 1.

Figure 4 is an enlarged sectional elevation taken on the line 4—4, Figure 3, illustrating the position of the circuit closing device in circuit open position.

Figure 5 is a sectional elevation extending transversely through the device of Figure 4, the section being taken on the line 5—5, of that figure.

It will be understood that for purposes of clarity of illustration the requisite elements have been shown in simplified form, and that their position and general arrangement, as well as relative sizes, may be substantially changed whenever desired. In the drawings the various elements are supported by a frame consisting of suitable standards 1 and horizontal frame members 2. The shearing roll is shown at 3.

The shearing roll carries suitable spirally arranged shear blades 3x, and, in the present embodiment, the roll at its ends is provided with shafts 4, 4x, which are received in the bearing

bosses 5, 5x at the outer ends of lever arms 6, 6x. These lever arms extend downwardly and carry at their lower ends apertured sleeves fixed upon a rock shaft 7 extending transversely of the frame and suitably journaled in bearing bosses carried by the latter as indicated at 8.

Carried by shaft 7 are depending crank arms 9, each of which at its lower end is pivoted to a link 10 which, in turn, is pivoted to a short upwardly extending crank arm 11 fixed to a rock shaft 12. Rock shaft 12 is journaled in the bearing bosses of two brackets 13 each carried by one of the standards 1. One of the two brackets is illustrated in Figure 1.

At one end of shaft 12 there is fixed thereto a hand lever 14 which at its outer end is formed with a threaded aperture to receive a vertical adjusting screw 15 provided with a lock nut 16. It will be seen that the operator by grasping the handle of lever 14 and moving the latter downwardly will effect the movement of the shear holding lever arm 6, in the direction of the arrow, Figure 1, the shear thus being raised. In practice, the shear need not be raised to the extent that the drive gears therefor will be brought out of mesh, the distance required being but a very small fraction of an inch, thereby clearing the seam.

Means are provided for power operating lever 14 and for automatically throwing the power device into and out of operation, and this means will now be described.

Mounted forwardly of the shear is a switch closing device. This device includes a feeler or shoe which rides upon the fabric. The shoe may be arranged to extend transversely of the fabric piece or longitudinally thereof. For convenience of illustration, the shoe is shown in the drawings as arranged longitudinally of the fabric, being shown at 17. The shoe is fixed to a yoke 18 pivotally held by pivot point members 19 in an adjustable frame 20 which, in turn, is pivotally carried by means of pivot point 21 in a fixed yoke frame 22. Frame 22 is carried by a rod arm 23 which, in turn, may be carried by a bracket 24 on the frame.

The feeler or shoe 17 has at its top a contact point 25 adapted to make contact with a contact screw 26 threaded in a member of the pivoted and adjustable frame 20. Electric current is led to the said frame 20 via positive wire 27, Figure 3 and a return wire 28 is connected to the pivoted frame 18 which carries contact point 25, thus enabling the closing of a circuit leading to a solenoid valve actuator later to be described.

The fixed frame 22 carries a rigid arm 29 having a threaded aperture at its end to receive an adjusting screw 30, which screw at its lower end is rotatably connected to the adjustable frame 20. Inasmuch as the shoe 17 is freely pivoted the adjustment in the height of frame 20 effected by means of screw 30 will exactly determine the distance between the contacts 25 and 21 for any given thickness of fabric and that distance will always be slightly less than the increased thickness given by the seam, so that when the seam passes under the shoe 17, as indicated in Figure 5, contact point 25 will meet adjustable contact screw 21, which, of itself, provides fine adjustment.

When the circuit closer closes the circuit, a solenoid valve actuator, generally indicated at 31, Figure 1, is thrown into action. Prior to such action the parts will be in the position shown in Figure 1. A fluid pressure line 32 communicates with the interior of valve casing 33 but is closed because valve head 34 depending from solenoid core 31x is in lowermost position. When the circuit is closed the movement of core 31x upwardly raises valve head 34 to the position of Figure 2 and a clear passageway is provided through valve casing 33 to a fluid pressure pipe 32x communicating with the interior of cylinder 35. Within the cylinder is a piston 36 carrying an upwardly extending piston rod 37 which passes through a packing gland at the top of the cylinder and contacts with adjusting screw 15.

For retraction of the piston, any suitable means may be employed, that illustrated in the drawings being a retraction spring 38. The piston has a quick but short rise because the energization of the solenoid is but momentary and the valve head 34 is almost instantly returned to initial position. In its return to initial position the valve head not only closes fluid pressure pipe 32 but opens the interior of the cylinder below the piston to the atmosphere via air discharge ports *a* and *b* in the valve casing, so that the spring 38, or merely the gravitational effect of the shear in its return will restore the piston to the position of Figure 1.

In the drawings a cloth piece is indicated at C and a seam at S, Figure 5. Any suitable drive for the shear may be provided, that indicated in the drawings being a belt 39 leading to a pulley 40 carried by a shaft 41 underlying the shear shaft 4, such shaft 41 carrying a gear 42 in mesh with a gear 43 carried by shaft 4.

It will be noted that in the embodiment illustrated in the drawings at Figure 1 the hand lever 14 is formed with an extension which directly receives the adjusting screw 15, and that an alternative construction is indicated in Figure 3 wherein an arm 44 carried by shaft 12 serves the same function as the hand lever extension of Figure 1. In such latter case the solenoid and power actuator may be disposed centrally of the machine instead of at the side.

Various modifications may be made in the form and arrangement of the elements illustrated in the drawings without departing from the spirit of the invention.

Having described my invention, what I claim and desire to secure by Letters Patent, is as follows:

1. A fabric-shearing machine comprising a rotary shear, a pivotal mounting for said shear, a lever and link connection applied to said pivotal mounting, a piston device for actuating said lever

and link connection through fluid pressure, a source of fluid pressure connected to the piston device, a solenoid valve controlling the admission of fluid to the piston device, an electric circuit including said solenoid valve, said circuit normally being open, and a circuit-closing device including two contact members, one carrying a shoe adapted to ride upon a length of fabric in its passage to the rotary shear, and means for adjusting the distance between the two contact members.

2. A fabric-shearing machine constructed in accordance with claim 1, in which the circuit-closing device comprises a carrier adapted for rigid mounting, a frame pivotally supported by said carrier, means for manually adjusting the position of the pivotal frame relatively to the carrier, a contact member carried by the pivotal frame, and a supplemental frame pivoted to the first-named frame and carrying a shoe adapted to ride upon the fabric in its passage to the rotary shear and also carrying a contact for engagement with the first-named contact when the shoe rides over a seam.

3. In a fabric-shearing machine constructed in accordance with claim 1, a circuit-closing device comprising a yoke member having pivot pins on its yoke arms, a frame held for swinging movement on said pivot pins, an adjusting screw carried by the frame and engaging the yoke member whereby the frame may be raised and lowered, a supplemental frame pivotally carried by the first-named frame and having a shoe adapted to ride upon a length of fabric in its passage to the shear, coacting contact members being carried by the first and second frames, and means for relatively adjusting said contact members.

4. A fabric-shearing machine constructed in accordance with claim 1, in which the pivotal mounting for the rotary shear comprises a pair of swinging arms carried upon a fixed support, a link connection leading to said arms, a hand-operated lever for actuating said link connection, and means intermediate said hand-operated lever and the piston device for adjusting the effective action of the piston device upon the lever.

5. In a fabric shearing machine and in combination with a power-driven rotary shear member and means for feeding a length of fabric composed of a plurality of fabric pieces joined by seaming, of a mounting for the shearing member movable to carry said member bodily away from the fabric, means for imparting a quick movement to said mounting and including an electrical device and a normally open circuit in which said device is disposed, and a circuit-closing member in said circuit and including a device adapted to ride upon a length of fabric in its movement toward the shearing member and adapted to close the circuit by engagement with the seams and the means for imparting movement thereto comprising opposed arms pivoted intermediate their lengths to a fixed support, a rock shaft, arms rigidly carried by the rock shaft, links connecting the rock shaft arms with the mounting arms, a manually operable lever for actuating said rock shaft, a piston device engaging said manually operable lever, means for leading fluid under pressure to said piston device, and a solenoid actuated valve for controlling the flow of said fluid, said solenoid actuated valve being in the normally open circuit.
